[57] ABSTRACT

Device for the distortion-free conversion of a signal voltage into a signal current or vice versa which comprises an input transistor having two main electrodes. A high-resistance current supply source is included between the first main electrode and a supply point, while this main electrode is also connected via a current feedback path to the control electrode of a first transistor the main current path of which is connected in the circuit between the second main electrode of the input transistor and another supply point, the output of the device being a point of the latter circuit.

DEVICE FOR CONVERTING AN INPUT VOLTAGE INTO AN OUTPUT CURRENT OR VICE VERSA

The invention relates to a device for the substantially distortion-free conversion of a signal voltage into a signal current or vice versa, which device comprises a first and a second control input and an output for the current or voltage, the first control input being connected to the control electrode of an input transistor which further has a first and a second main electrode between which extends its main current path, while the second main electrode also forms the second control input.

In a known device of this kind the control electrode is constituted by the base, the first main electrode by the collector and the second main electrode by the emitter of a transistor. The device has a quiescent current setting (D.C.) on which signals may be superposed. A voltage is applied to the base of the transistor and an output current may be derived from the collector. The emitter of the transistor is connected, for example through a resistor, to a point of constant potential. The output signal current of this device is equal to

$$i_c = V - V_{be}/R - i_b \quad (1)$$

where i_b is the base signal leakage current of the transistor, R is the resistance value of the emitter resistor, V is the amplitude of the signal voltage applied to the base of the transistor and V_{be} is the signal voltage between the base and the emitter of the transistor. The values of i_b and V_{be} are dependent on the current and on the temperature. This current dependence of V_{be} means that distortion will occur in the output current of the device. Hence the said device is not very suitable for use in highly accurate multipliers and gyrators which have to satisfy stringent quality requirements.

It is an object of the invention to provide a device of the said kind in which a highly accurate voltage to current or current to voltage conversion is effected substantially independently of the transistor parameters and which is highly suited for use in gyrators, multipliers and differential amplifiers.

The invention is characterized in that there is included in the circuit between the first main electrode and a supply point a high-resistance current source, while furthermore this main electrode is connected, via a current feedback path, to the control electrode of a first transistor the main current path of which is connected in the circuit between the second main electrode of the input transistor and another supply point, the output being a point of the latter circuit.

Embodiments of the invention will now be described, by way of example, with reference to the accompanying diagrammatic drawings, in which:

FIG. 1 is a circuit diagram of a first embodiment of the device according to the invention,

FIG. 2 is a circuit diagram of a second embodiment of the device according to the invention,

FIG. 3 is a circuit diagram of a third embodiment of the device according to the invention,

FIG. 4 is a circuit diagram of a fourth embodiment of a device according to the invention,

FIG. 5 is a circuit diagram of a differential amplifier using a device according to the invention,

FIG. 6 is a circuit diagram of an alternative output circuit for deriving the output current,

FIG. 7 is a circuit diagram of a further alternative output circuit for deriving the current,

FIG. 8 is a circuit diagram of a symmetrical voltage-controlled current supply source employing devices according to the invention, and

FIG. 9 is a circuit diagram of a direct-current supply circuit employing devices according to the invention.

Referring now to FIG. 1, the input electrode of the device is constituted by the base of a transistor T_o . The first electrode of the transistor T_o is constituted by its collector and the second electrode by its emitter. The collector of the transistor T_o is connected to a supply point of constant potential via a high-resistance to form a current supply source S . The emitter of the transistor T_o is directly connected to the output C of the device via the collector-emitter path of a transistor T_1 .

The base of the transistor T_1 is connected to the collector of the transistor T_o through the collector-emitter path of a transistor T_2 . The base of the transistor T_2 is connected to the emitter of the transistor T_o and also, through a resistor R , to a point of constant potential.

The operation of the circuit shown in FIG. 1 is as follows. The signal i which will flow through the resistor R as a result of a signal voltage V applied to the base of the transistor T_o is

$$i = V - V_{be}/R \quad (2)$$

where R is the resistance value of the resistor R and V_{be} is the base emitter signal voltage of the transistor T_o . The output i_c then will be

$$i_c = i - i_{bo} \quad (3)$$

If $V_{be} \ll V$ and $i_{bo} \ll i$, the conversion of voltage to current is ideal (independent of the transistor parameters). Because only a small part of the signal current (i_{b1}) flows, via the base path of the transistor T_1 and via the transistor T_2 , through the input transistor T_o , V_{be} is small and the leakage current i_{bo} also is small, much smaller ($\sim \beta_1 x$) than if a single transistor were used. The ideal condition

$$i_c = V/R \quad (4)$$

is approximated to with a degree of accuracy higher by a factor of β . The distortion of the signal due to the non-linear characteristics of the transistors is also reduced by a factor of β . It is true that direct current is supplied to the circuit via the current supply source S , but this source is selected to have so high an impedance that no signal current leaks away. The device T , i.e., the portion of FIG. 1 surrounded by dotted lines, may be regarded as an artificial pnp transistor having a base b , an emitter e and a collector c . The base collector current gain factor of this artificial transistor is about equal to β^2 . Its transconductance is about equal to βS , where S is the transconductance of the transistor T_o . The artificial pnp transistor may be used as a high quality direct-current supply source. This is effected by making $i = 0$, which is the case when the emitter e of the equivalent transistor is floating. The output direct current

then will be equal to the direct current supplied by the source S. The resulting direct-current supply source at its output c has a very high output impedance which may be of the order of 1 giga-ohm.

FIG. 2 shows a device for converting an input current into an output voltage in a substantially distortion-free manner. The base b of the artificial pnp transistor T is connected to a point of constant potential, for example earth. A signal current i is supplied to the emitter e via a current supply source S_1 . The collector c of the artificial transistor is connected to a point of constant potential via a resistor R. The operation of the device shown in FIG. 2 is substantially equal to that of the device shown in FIG. 1. A signal current i is supplied to the emitter and a signal voltage substantially equal to iR may be derived from the collector.

The input electrode of the device shown in FIG. 3 is constituted by the base of the transistor T_o . The first electrode of the transistor T_o is constituted by the emitter of this transistor and the second electrode by its collector. The emitter of the transistor T_o is connected to a constant-potential supply point via a high-resistance to form a current supply source S. The collector of the transistor T_o is connected to a supply point of the device via the main current path of a transistor T_1 . The base of the transistor T_1 is connected to the emitter of the transistor T_o via the main current path of a transistor T_2 . The base of the transistor T_2 is connected to the collector of the transistor T_o and, via a resistor R, to a point of constant potential. The base of the transistor T_o is connected to a signal voltage supply source V.

The operation of the device shown in FIG. 3 is as follows.

Owing to the signal voltage V applied to the base b the resistor R will be traversed by a signal current i which is equal to

$$i = V - V_{be}/R \quad (5)$$

where V_{be} is the signal voltage between the two control electrodes b and e. The output current of the device may be derived at c and is equal to

$$i_c = i - i_{bo} \quad (6)$$

where i_{bo} is the signal current which leaks away through the base of the transistor T_o . Because from the base of the transistor T_1 only a small part of the main current is fed back via the transistor T_2 and the transistor T_o , i_{bo} is very small, as are the base-emitter signal voltages of the transistors T_o and T_2 which together form V_{be} . The device T of FIG. 3 may be regarded as an artificial npn transistor with b as the base, e as the emitter and c as the collector. The base-collector current gain factor is about β^2 and the transconductance is about $1/(1/\beta S_o + 1/\beta S_2)$, where S_o and S_2 are the transconductances of the transistors T_o and T_2 respectively. In the same manner as shown in FIG. 2 with respect to the artificial pnp transistor the artificial npn transistor may be operated in common-base connection. For this purpose the base b is connected to a point of constant potential. A signal current i may be supplied to the emitter e, and the collector c may be connected to a point of constant potential through a re-

sistor. The signal voltage across this resistor then will be substantially iR Volts.

In FIG. 4 the input electrode of the device is constituted by the base of the transistor T_o . The first electrode of the transistor T_o is constituted by the collector of this transistor and the second electrode by its emitter. The collector of the transistor T_o is connected to a supply point of constant potential via a high-resistance to form a current supply source S. The emitter of the transistor T_o is connected to the output c of the device via the main current path of a transistor T_1 . The base of the transistor T_1 is connected to the collector of the transistor T_o via the series combination of diodes D_1 and D_2 , the emitter-base path of a transistor T_3 and the collector-emitter path of a transistor T_2 . The second terminal c of the device is connected to a high-resistance current supply source S_1 via the collector-emitter path of the transistor T_3 . The base of the transistor T_2 is connected to the emitter of the transistor T_o and also, via a resistor R, to a point of constant potential. The base of the transistor T_1 is connected to the high-resistance current supply source S_o . A diode D_o is connected between the base and the emitter of the transistor T_o .

The operation of the circuit shown in FIG. 4 is as follows. The signal current i which flows through the resistor R as a result of a signal voltage V applied to the base of the transistor T_o satisfies the relationship (2). The transistor T_1 will pass a collector signal current of $(i - i_1)$ amperes, where i_1 is the signal current which largely flows through the emitter-collector path of the transistor T_o . Because the collector of the transistor T_o is connected to the high-resistance current supply source S, the signal current i_1 will also flow through the emitter-collector path of the transistor T_2 to the base of the transistor T_3 . The collector-emitter path of the transistor T_3 will pass a signal i_2 . Because the emitter of the transistor T_3 is connected to the high-resistance current supply source S_1 and because the diode D_1 is connected to the high-resistance current supply source S_o , the signal current i_2 will flow via the diodes D_1 and D_2 of the base of transistor T_1 . We now have the following relationships for the currents i , i_1 and i_2 :

$$i_1 \approx i_2/\beta \text{ and } i_2 \approx i/\beta$$

where β is the collector-base current gain factor of the transistors T_o , T_1 and T_3 . Thus, the signal current flowing through the main current path of the input transistor T_o is about $1/\beta^2$. As a result the signal current, which always goes through the base of the input transistor T_o , will be about i/β^3 , that is smaller by a factor of β than in, for example, the device shown in FIG. 1. Consequently the variations in the base-emitter threshold voltage V_{be} of the transistor T_o are reduced by a factor of β^2 , so that the distortion in the output signal of the device shown in FIG. 4 will also be reduced by a factor of β^2 as compared with the distortion in a single transistor.

The device shown in FIG. 4 also may be regarded as an artificial pnp transistor in which b is the base, e is the emitter and c is the collector. The base-collector current gain factor of this artificial transistor is about β^3 . The transconductance of this pnp equivalent transistor is about $\beta^2 S_o$, where S_o is the transconductance of the transistor T_o .

In the device shown in FIG. 4 the collector of the first transistor T_3 is connected to the emitter of the input

transistor T_o via the emitter-collector path of one transistor. However, the collector of this first transistor may alternatively be connected to the emitter of the input transistor T_o via the series connection of the emitter-collector paths of a plurality (n) of transistors, the base of each of the transistors of the series combination being connected to the emitter of the succeeding transistor via voltage shifting means, while the output of the device then will be constituted by the emitter of that transistor of the series combination which is connected to the input transistor. If, for example, the emitter of the input transistor is connected to a point of constant potential via a resistor and a signal voltage is applied to the base of the input transistor, the base signal leakage current of the input transistor will be smaller than the signal current passed by the transistor connected to the input transistor by a factor of β^{n+1} . As a result the distortion in the output signal will be reduced by a factor of β^n with respect to the distortion of a single transistor. The equation (4) is approximated to with an accuracy which is β^n times higher.

FIG. 5 shows a differential amplifier employing two artificial pnp-transistors as shown in FIG. 1. The emitters of these artificial pnp-transistors are connected respectively to opposite terminals of a resistor R . A voltage v is applied between the bases of the artificial pnp-transistors. Their collectors are connected to a point of constant potential through D_3 and D'_3 respectively. The diodes D_3 and D'_3 may be identical transistors, for example T_3 and T'_3 , in which the base and the collector are short-circuited. The base of the transistor T_3 (T'_3) is connected to the collector of the diode D_3 (D'_3 respectively), while all the four emitters are connected to one another and to a point of constant potential. Now

$$i = V - 2V_{be}/R \quad (8)$$

and

$$i_c = i - i_{bo} \quad (9)$$

while the current mirror ($D_e T_e$ and $D_3' T_3'$) is least accurate

$$i_o \approx i_c(1 - 2/\beta) \quad (10)$$

FIG. 6 shows an alternative embodiment of the current mirror in which the transistor T_1 (T_1') is combined with the diode D_3 (D_3' respectively).

FIG. 7 shows a much more accurate alternative embodiment of a current mirror including three transistors in combination with the transistor T_1 . In this embodiment

$$i_o \approx i_c(1 - 2/\beta_2) \quad (11)$$

The crossing base currents i_{b1} and i_{b4} largely compensate each other.

The amplifier of FIG. 5 uses pnp artificial transistors of the type shown in FIG. 1. Obviously, as an alternative pnp artificial transistors as shown in FIG. 4 or npn artificial transistors as shown in FIG. 3 may be used. To

improve the high-frequency behaviour of the artificial pnp transistors a diode may be included in the base circuit of the transistor T_2 , as is indicated in broken lines in FIGS. 1 and 2, or the emitter-collector path of the transistors T_2 and T_2' may each be shunted by a capacitor, as is indicated in broken lines in FIG. 5. The addition of additional direct current by means of the current supply S_0 (FIGS. 1 and 2) also improves the high-frequency behaviour (driving). The diode connected between the emitter and the base of the transistor T_o (shown in broken lines in FIGS. 1, 2 and 4) improves the bias setting of the artificial pnp transistor and also serves as a protection for the base-emitter diode of the transistor T_o .

15 The differential amplifier shown in FIG. 5 may readily be converted to a multiplier. For this purpose the emitters of the transistors T_3 and T'_3 are connected to a point of constant potential via a common current supply.

20 Assuming the said current supply to supply a current of $2I(1+x)$ amperes and the voltage applied to the input to be Y volts, the output current i_o contains a component I_{xy} .

FIG. 8 shows a symmetrical voltage-controlled current supply using two artificial pnp transistors T and T' . The collector c of the equivalent transistor T is connected via a current supply S_1 to a point of constant potential and also via a resistor Z_1 to the collector c' of the artificial transistor T' . The collector c' of the artificial transistor T' is also connected to a point of constant potential via an impedance Z_2 . The emitter e of the artificial transistor T is connected via a resistor R to the emitter e' of the artificial transistor T' . When a signal voltage V is applied between the two base electrodes b and b' of the artificial transistors T and T' respectively an output signal current will flow through the load impedance Z_1 , which current is substantially equal to V/R amperes. The two equations (8) and (9) apply to the currents i and i_c . In the embodiment shown in FIG. 8 two artificial pnp transistors are used. Obviously instead of two artificial pnp transistors two artificial npn transistors as shown, for example, in FIG. 3 may be used. Voltage-controlled current supplies as shown in FIG. 8 enable, for example, the construction of highly accurate gyrators.

50 The current supply sources S and S' used in the embodiment shown in FIG. 8 may be of the type shown in FIG. 9. The current supply shown in FIG. 9 includes an artificial pnp transistor T . The base of this artificial transistor is connected via the series combination of a diode D_1 and a resistor R_1 to a point of constant potential U_b^+ . The base of the artificial pnp transistor T is also connected via a resistor R_2 to another point of constant potential. The emitter of the artificial pnp transistor is floating. From the collector c of the artificial pnp transistor a direct current may be derived which is equal to the direct current passed by the transistor T_3 . This current is determined by the current flowing through the branch R_1 , D_1 and R_2 and by the value of a resistor R_3 .

55 The current supply source shown in FIG. 9 may be used, for example, as the current supply S in FIGS. 1, 2, 4 and 5. In FIG. 4 the current supply S_0 may simply be realized by including an additional transistor T'_2 in the current supply shown in FIG. 9. The collector of this transistor T'_2 is connected to the base of the transistor T_1 of FIG. 4.

Obviously, the invention is not restricted to the embodiments shown and to one skilled in the art many modifications are possible without departing from the scope of the invention. For example, both bipolar transistors and field-effect transistors may be used. Furthermore field-effect transistors having an n-channel region or a p-channel region and also both of the enhancement type and of the depletion type may be used.

What is claimed is:

1. A transistor circuit which acts as an artificial transistor having a high β and high transconductance, comprising:

a high internal resistance constant current supply source;

a first transistor having a base electrode and collector and emitter electrodes forming a first current path;

a second transistor having a base electrode and collector and emitter electrodes forming a second current path, the first and second current paths being electrically connected at one end thereof to said constant current supply source to maintain currents through the first and second current paths the sum of which always totals the current maintained by said constant current supply source, the other end of the first current path being electrically connected to the base electrode of said second transistor; and

a third transistor having a base electrode and collector and emitter electrodes forming a third current path, the third current path being electrically connected at one end to the first current path, the base electrode of said third transistor being electrically responsive to the current flowing in the second path,

whereby the base electrode of said first transistor, the base electrode of said second transistor and the other end of the third current path electrically act as if they were base, emitter and collector electrodes respectively of an artificial transistor having a high β and high transconductance.

2. A transistor circuit as defined in claim 1 wherein: said first and third transistors are of NPN type and said second transistor is of PNP type;

the collector electrode of said first transistor and the emitter electrode of said second transistor are both electrically connected to the current supplying end of said constant current supply source;

the base electrode of said second transistor is electrically connected to both the emitter electrode of said first transistor and the collector electrode of said third transistor; and

the collector electrode of said second transistor is electrically connected to the base electrode of said third transistor,

whereby the base electrode of said first transistor, the base electrode of said second transistor and the emitter electrode of said third transistor electrically act as if they were base, emitter and collector electrodes respectively of an artificial PNP transistor having a high β and high transconductance.

3. A transistor circuit as defined in claim 1 wherein:

said first, second and third transistors are of NPN type;

the emitter electrodes of said first and second transistors are both electrically connected to the current

receiving end of said constant current supply source;

the base electrode of said second transistor is electrically connected to both the collector electrode of said first transistor and the emitter electrode of said third transistor; and

the collector electrode of said second transistor is electrically connected to the base electrode of said third transistor,

10 whereby the base electrode of said first transistor, the base electrode of said second transistor and the collector electrode of said third transistor electrically act as if they were base, emitter and collector electrodes respectively of an artificial NPN transistor having a high β and a high transconductance.

4. A transistor circuit for substantially distortion-free conversion of a voltage signal into a current signal, comprising a transistor circuit as defined in claim 1 and further comprising:

a first impedance electrically connected at one end thereof to the base terminal of said second transistor;

a second impedance electrically connected at one end thereof to the other end of the third path; and

20 a voltage source electrically connected between the other ends of said first and second impedances, whereby a voltage signal applied to the base terminal of said first transistor is converted into a proportionate substantially distortion-free current signal through said second impedance.

5. A transistor circuit as defined in claim 4 wherein:

said first and third transistors are of NPN type and said second transistor is of PNP type;

the collector electrode of said first transistor and the emitter electrode of said second transistor are both electrically connected to the current supplying end of said constant current supply source;

the base electrode of said second transistor is electrically connected to both the emitter electrode of said first transistor and the collector electrode of said third transistor;

the collector electrode of said second transistor is electrically connected to the base electrode of said third transistor;

said second impedance is electrically connected at one end thereof to the emitter electrode of said third transistor; and

said voltage source is electrically connected between said impedances with the side of more negative potential connected to said second impedance.

6. A transistor circuit as defined in claim 4 wherein:

said first, second and third transistors are of NPN type;

the emitter electrodes of said first and second transistors are both electrically connected to the current receiving end of said constant current supply source;

the base electrode of said second transistor is electrically connected to both the collector electrode of said first transistor and the emitter electrode of said third transistor;

the collector electrode of said second transistor is electrically connected to the base electrode of said third transistor;

said second impedance is electrically connected at one end thereof to the collector electrode of said third transistor; and

said voltage source is electrically connected between said impedances with the side of more positive potential connected to said second impedance.

7. A transistor circuit for substantially distortion-free conversion of a current signal into a voltage signal, comprising a transistor circuit as defined in claim 1 and further comprising:

an impedance electrically connected at one end thereof to the other end of the third path; and a voltage source electrically connected between the base electrode of said first transistor and the other end of said impedance,

whereby a current signal applied to the base terminal of said second transistor is converted into a proportional substantially distortion-free voltage signal across said impedance.

8. A transistor circuit as defined in claim 7 wherein:

said first and third transistors are of NPN type and said second transistor is of PNP type;

the collector electrode of said first transistor and the emitter electrode of said second transistor are both electrically connected to the current supplying end of said constant current supply source;

the base electrode of said second transistor is electrically connected to both the emitter electrode of said first transistor and the collector electrode of said third transistor;

the collector electrode of said second transistor is electrically connected to the base electrode of said third transistor;

said impedance is electrically connected at one end thereof to the emitter electrode of said third transistor; and

said voltage source is electrically connected between the base electrode of said first transistor and the other end of said impedance with the side of more negative potential connected to said impedance.

9. A transistor circuit as defined in claim 1 and further comprising:

a fourth transistor having a base electrode and collector and emitter electrodes forming a fourth current path, the fourth current path being electrically connected at one end thereof to the other end of the third current path;

two diodes electrically connected in series between the base electrode of said third transistor and the other end of said fourth current path;

a second high internal resistance constant current supply source connected at one end thereof to the other end of the fourth current path; and

a third high internal resistance constant current supply source connected at one end thereof to the base electrode of said third transistor, the second and third constant current supply sources biasing said third and fourth transistors without thereby shunting signal current therefrom, the base electrode of said fourth transistor being electrically responsive to the current flowing in the second path,

whereby the base electrode of said first transistor, the base electrode of said second transistor and the other end of the third current path electrically act as if they were base, emitter and collector electrodes respec-

tively of an artificial transistor having a high β and high transconductance.

10. A transistor circuit as defined in claim 9 wherein:

said first, third and fourth transistors are of NPN type and said second transistor is of PNP type;

the collector electrode of said first transistor and the emitter electrode of said second transistor are both electrically connected to the current supplying end of said first constant current supply source;

the base electrode of said second transistor is electrically connected to both the emitter electrode of said first transistor and the collector electrode of said third transistor;

the emitter electrode of said third transistor is electrically connected to the collector electrode of said fourth transistor;

the emitter electrode of said fourth transistor and the emitter side of said series connected diodes are both electrically connected to the current receiving end of said second constant current supply source;

the base electrode of said third transistor and the collector side of said series connected diodes are both electrically connected to the current supplying end of said third constant current supply source; and the collector electrode of said second transistor is electrically connected to the base electrode of said fourth transistor,

whereby the base electrode of said first transistor, the base electrode of said second transistor and the emitter electrode of said third transistor electrically act as if they were base, emitter and collector electrodes respectively of an artificial PNP transistor having a high β and high transconductance.

11. A transistor circuit for substantially distortion-free conversion of a voltage signal into a current signal, comprising a transistor circuit as defined in claim 9 and further comprising:

a first impedance electrically connected at one end thereof to the base terminal of said second transistor;

a second impedance electrically connected at one end thereof to the other end of the third path; and

a voltage source electrically connected between the other ends of said first and second impedances, whereby a voltage signal applied to the base terminal of said first transistor is converted into a proportionate substantially distortion-free current signal through said second impedance.

12. A transistor circuit as defined in claim 11 wherein:

said first, third and fourth transistors are of NPN type and said second transistor is of PNP type;

the collector electrode of said first transistor and the emitter electrode of said second transistor are both electrically connected to the current supplying end of said first constant current supply source;

the base electrode of said second transistor is electrically connected to both the emitter electrode of said first transistor and the collector electrode of said third transistor;

the emitter electrode of said third transistor is electrically connected to the collector electrode of said fourth transistor;

the emitter electrode of said fourth transistor and the emitter side of said series connected diodes are both electrically connected to the current receiving end of said second constant current supply source;

the base electrode of said third transistor and the collector side of said series connected diodes are both electrically connected to the current supplying end of said third constant current supply source;

the collector electrode of said second transistor is 10 electrically connected to the base electrode of said fourth transistor;

said second impedance is electrically connected at one end thereof to the emitter electrode of said third transistor; and

said voltage source is electrically connected between

said impedances with the side of more negative potential connected to said second impedance.

13. A transistor circuit as defined in claim 1 and further comprising a high internal resistance constant current supply source electrically connected at one end thereof to the other end of the second current path.

14. A transistor circuit as defined in claim 1 and further comprising a diode electrically connected between the base electrode of said first transistor and the base electrode of said second transistor.

15. A transistor circuit as defined in claim 1 and further comprising a capacitance electrically connected from the emitter terminal of said second transistor to the collector terminal thereof.
